UNITED STATES PATENT OFFICE.

AUGUSTUS L. ENGELBACH, OF DENVER, COLORADO.

SLICING-MACHINE FOR VEGETABLES AND FRUITS.

1,323,073.

Specification of Letters Patent. Patented Nov. 25, 1919.

Application filed January 13, 1919. Serial No. 270,889.

To all whom it may concern:

Be it known that I, AUGUSTUS L. ENGELBACH, a citizen of the United States of America, residing at the city and county of Denver and State of Colorado, have invented new and useful Slicing-Machines for Vegetables and Fruits, of which the following is a specification.

This invention relates to improvements in slicing or cutting machines for vegetables and fruits.

The primary object of the invention is to provide a machine by which potatoes can be cut into either long, narrow strips, which, when cooked are commonly known by the appellation of "Julien," or "shoe string" potatoes; or into strips which are thicker and wider than the "shoe string" variety, and which, when cooked, are known as "French fried."

Further, to provide a machine having a circular, rotatable drum provided with a plurality of spaced rotary slitting knives mounted on a common shaft, and a transversely arranged slicing knife located rear of the slitting knives, whereby a potato held against the face of the drum is first given a plurality of parallel slits and the said slitted portion is then sliced off to the depth of the slits by the slicing knife, thereby producing a series of string-like pieces of potato of uniform size, upon each rotation of the drum, means being provided for holding the potatoes against rotary movement and also for pressing the same against the drum during the slitting and slicing action.

These and other objects to be hereinafter set forth, are accomplished by the device illustrated in the accompanying drawings, in which:

Figure 1 is a side elevation of the improved machine.

Fig. 2 is a horizontal, sectional view on the line 2—2 of Fig. 1.

Fig. 3 is an end thereof, the base plate being omitted for lack of space.

Fig. 4 is a front view, partly in section, of the rotary member which supports the slitting and slicing knives.

Fig. 5 is a face view, partly in section, of the member shown in Fig. 4, illustrating the manner of adjustably supporting the rotary slitting knives or disks.

Fig. 6 is a fragmentary sectional view

showing the opening or mouth of the stationary casing of the machine, in which a potato is placed to be acted upon by the slitting and slicing knives, and also the presser by which the potato is held against the rotary member.

Fig. 7 is a plan view of the said presser.

Fig. 8 is a fragmentary sectional view on the line 8—8 of Fig. 6, illustrating the manner of supporting the wooden abutment which forms the end wall of the mouth portion of the machine.

Fig. 9 is a detail plan view showing the mouth portion of the machine and the wooden abutment wall. And

Fig. 10 is a fragmentary sectional view illustrating a modification in the manner of supporting and adjusting the rotary slitting knives.

The present methods of preparing potatoes to be served as either "shoe string" or "French fried" are both slow and laborious, and in most instances the work is accomplished simply by first making a series of slits in the potato, with an ordinary knife, and then slicing off the slit portion, and continuing this operation of first slitting and then slicing. Such a method is necessarily slow, and the results are at best, unsatisfactory, as it is impossible to produce strings of uniform size. The present invention, however, overcomes these objections by producing a product which is of uniform size throughout, the work being accomplished with great rapidity, and requiring no skill on the part of the person operating the machine.

Referring to the accompanying drawings:

The numeral 1, refers to the base plate of the machine, and 2, a semi-cylindrical housing or casing member which is connected to the base plate by legs 3, the plate, legs and housing member being in the form of an integral casting. On one edge of the housing member are formed oppositely arranged lugs or ears 4, which are provided with holes which are in axial line; and on the opposite edge of the housing member is formed a bifurcated lug 5, in which is mounted one end of a swinging bolt 6. A semi-cylindrical casing member 7, rests upon the casing member 2, and this latter member 7, has apertured ears 8, on one of its edges, which lie between and bear against the ears 4, and a pin 9, is passed through

the ears 4 and 8, thereby hinging the members 2 and 7 together. The member 7, has a bifurcated lug 10, which rests upon the lug 5, of the member 2, and the bolt 5 is swung to project through the bifurcation in the said lug 10, and a thumb nut 11 is screwed upon the bolt 5 and against the lug 10, thereby securely holding the members 2 and 7 together, to form a cylindrical housing, in 10 which is rotatably mounted a drum 12, to be presently described.

One side of the cylindrical housing is open, and the opposite side of each housing member is in the form of a wall, which is 15 preferably of a light open work design, as shown, the edges to the walls engaging when the housing is closed, as shown by Fig. 1. An axial bearing hub 13, is cast integral with the wall of the casing member 2, and a 20 second hub 14, is integrally connected to the hub 13, by an arm or bracket 15, the two hubs being in alinement.

The drum 12, which rotates within the housing is of slightly less diameter than the 25 housing, and is provided with an axial hub 16, which is connected to spokes 17, which are also connected to the band portion of the drum, as most clearly shown by Fig. 4. The hub 16, extends inward from the spokes 30 17, and connects with the rear inclined wall of a chute 18, the drum and its various parts being in the form of an integral casting. A shaft 1^A is mounted in the hubs 13 and 14, and extends into the hub 16, of the drum, 35 and a set screw 1^B secures the hub to the shaft. The outer end of the shaft 1^A carries an arm 1^C, having a handle 1^P, by means of which the drum 12, may be rotated.

The chute 18 comprises a rear inclined 40 wall, side walls, and a front portion, which is in the form of a door 18^A, the inner end of which terminates in a semi-circular outwardly projecting rim 19, which acts in connection with a similar semi-circular rim 19^A, 45 on the inner end of the chute, to form a circular axial spout, as shown. The door 18, has a hinge lug 18^B, on one side thereof, which lies between, and is pivotally connected to ears 18^C, on the corresponding side 50 of the chute. The door is held normally in a closed position by a spring catch 18^D, which is secured to one side of the chute, and engages the adjacent edge of the door. The outer end of the chute is only partially 55 closed, a portion of the drum 12, which forms the outer wall 20 of the chute being omitted to leave an opening about half the width of the chute, as will be understood by reference to Fig. 4. This end wall 20 is 60 slightly inset from the face of the drum, and one end of a segmental resilient metal strip 21 is secured to the wall 20, and extends from one side of the chute to a point slightly beyond the end of the wall 20, and 65 upon the free end of this strip is secured a

transversely arranged slicing knife 22, which extends to within a slight distance of the adjacent edge 23, of the drum where the wall of the drum is omitted or cut away to form an opening into the chute, between the 70 said edge 23 and the opposing edge of the outer wall 20 of the chute. The space between the edge 23 and the cutting edge of the knife 22 determines the thickness of the slice severed from a potato, and this thickness may be increased or diminished by adjusting screws 24, in threaded apertures in the front edge portion of the wall 20, which bear against the under side of the segmental strip 21, to which the knife is secured, the 80 said screws being adapted to spring the strip 21 outward, and thus increase the distance between the edge 23 of the chute and the cutting edge of the knife, or to permit the strip 21 to spring inward, and thus diminish 85 the distance between the edge 23 and the cutting edge of the knife 22, the strip 21 being always under tension, which causes it to bear forcibly against the ends of the screws 24.

At a distance from the knife 22, of substantially one-fourth of the circumference of the drum 12, and in advance of the said knife, a transverse opening 25 is formed in the wall of the drum, through which project the slitting knives 26, which are arranged as follows: One of the spokes 17 of the rotary band is provided near its outer end with a countersunk slot 27, and diametrically opposite this slot is an ear or lug 28, which projects inward from the rim of the band and is provided with a slot 29, which opens out through the inner end of the said lug. A pin or screw 30, having a beveled head, is passed through the slots 27 and 29, 105 the beveled head of the screw resting in the countersunk slot 27, while the opposite end of the screw receives a nut 31, which is screwed against the lug 28, and thus clamps the head of the screw against the face of the 110 countersunk slot 27, whereby the screw is firmly held in any adjusted position within the slots 27 and 29.

Upon the screw 30 is rotatably mounted a sleeve 32, which extends from the spoke 17 115 to the lug 28, and upon this sleeve are mounted a series of spaced knife edge disks 26, which are separated by rings or washers 33, the width of the rings determining the space between the disks. In assembling the 120 disks upon the sleeve, one end of the said sleeve is flanged and the disks and spacing rings are then placed upon the sleeve in alternate order, and the opposite end of the sleeve is then upset or flanged so as to bear 125 against the last disk or ring, as the case may be, and the several disks and rings are thus securely clamped between the flanges on the opposite ends of the sleeve. The sleeve with the disks thereon is then held in the posi- 130

tion shown in Fig. 5; and the screw 30 is passed through the sleeve and clamped in position, in the manner previously described. The distance which the disks project beyond 5 the face of the band determines the depth of the slits made in the potato, and the slicing knife 22 is adjusted accordingly.

In order to more easily accommodate the machine to the two varieties of sliced product, namely, the "shoe string" variety and the "French fried" variety, it is desirable to have two sets of slitting disks, the set for producing the "shoe string" variety having disks which are much nearer together than 15 those which are to produce the "French fried" variety, and the slicing knife 22, is correspondingly adjusted.

An opening 34, is formed in the curved wall of the upper casing member 7, and this 20 opening is of sufficient length and width to accommodate large sized potatoes, and constitutes the mouth of the machine. Oppositely arranged side plates 35, project above the longer sides of the mouth and act in 25 conjunction with a removable end board 36, to confine the potato within the opening or mouth 34, in which position it bears upon the rotary band or drum 12. The end or abutment board 36 is supported in vertical 30 slots 37, in the side plates 35, the lower ends of which terminate in ledges 38, which limit the downward movement of the board, the board being formed with shoulders 39, as shown in Fig. 8, which rest on the said ledges. 35 The lower end of the board 36, extends slightly below the inner face of the casing member 7, and thus prevents the slitting knives from being outwardly adjusted far enough to contact with the casings, as, when 40 the knives engage the edge of the board it is a notification that further outward movement would cause them to contact with the casing. In practice, the slitting knives should project a slightly greater distance 45 beyond the face of the drum than the slicing knife, and though they should cut slightly into the edge of the board, the said board will offer no obstruction to the slicing knife, as the latter knife will pass beneath the edge of the board.

The potatoes are held against the rotary arm by a presser, of the form shown most clearly in Figs. 6 and 7, and which comprises a substantially concavo-convex plate 50 40, the under or concave face of which is formed with a plurality of spurs 41, which prevent slipping of the potato when the presser is applied. The rear end of the presser terminates in arms 42, which are 55 pivotally connected to upright arms or standards 43, which are formed on the upper casing member 7, the pivotal connection being accomplished by a pin 44, which is passed through holes in the ends of the said 60 arms 42 and 43, as shown.

In order to limit the downward movement of the presser, and thus prevent the same from contacting with the slicing and slitting knives, I provide an adjustable stop in the form of a screw 45, which enters a lug 46, formed on the casing member 7, the head of the screw being engaged by the rear end of the plate portion of the presser, when the presser reaches the limit of its downward movement, the limit being 70 determined by the adjustment of the screw. The upper side of the presser has formed thereon a handle or knob 47, by means of which the presser can be swung back to permit the insertion of a potato in the mouth 75 of the machine.

In Fig. 10 is illustrated a modification in the adjustment feature of the slitting knives. In this arrangement the disks are clamped upon the sleeve, which is mounted 80 in a pin or screw, in the manner hereinbefore described; but in the modification, the screw is secured in the end of a yoke 48, which is pivotally secured to ears 49, formed on the wall of the drum. The yoke 90 has a tail 50, the end of which has a threaded aperture. A screw 51, is passed through a hole in the wall of the drum, and through the threaded aperture in the end of the tail 50, and an expansion coil spring 52 surrounds the screw and bears at one end 95 against the tail 50, and at the other end against the wall of the drum, and by turning the screw, the yoke is swung on its pivot and the disks are projected through the 100 opening 25 in the drum far enough to slit the potato to the required depth.

In operation, the presser 40 is thrown back out of the mouth of the casing, and a potato, which has been previously pared, is 105 placed in the said mouth so as to rest upon the drum. The presser is then swung over and held against the potato, and the drum is rotated in the manner before described; the slitting knives first engage the face of the potato which is thus given a series of parallel slits, and the slicing knife then cuts off the slit portion, which drops into the chute 110 18, in the form of long narrow strips, which immediately pass out of the hopper through the axial outlet opening, which is large enough to prevent choking, and fall into a pan or dish which is placed to receive them. The base plate of the machine is provided with holes as shown, through which screws 120 or bolts may be passed to secure the machine to a bench or table. But the base plate may also be secured by clamps of a style in common use, and which I do not illustrate, as they do not form a part of this invention. 125 When desired, the slitting knives may be removed, and the slicing knives then act to cut the potato in thin slices, for "chips", or in thicker slices to be fried in the usual manner.

Having described my invention, what I claim as new and desire to secure by Letters Patent, is:

- 5 1. In a slicing machine of the character described, a rotatable drum having an opening in its face, a pin mounted in said drum and adjustable with respect to said opening, a sleeve rotatably mounted on the pin, having spaced disk knives thereon which project through the said opening, and a slicing knife mounted on the face of the drum, rear of the disk knives and adjustable toward and away from the said face of the drum.
- 10 2. In a slicing machine of the character described, a metal drum, one end of which is open, and having an integral inclosed chute provided with an axial, laterally discharging outlet, and an inlet which is formed in the face of the drum, a transverse, adjustable slicing knife on the drum above the said inlet and spaced slitting knives in advance of the slicing knife.
- 15 3. In a slicing machine of the character described, a metal drum, one end of which is open, and having an integral chute, the outer face of which is in the form of a door, said chute having an axial circular discharge spout, one half of which is formed on the door, while the other half is formed on the chute, the face of said drum having an opening therein, a transverse, adjustable

slicing knife on the drum above said opening, and spaced slitting knives on the drum in advance of the slicing knives.

35

4. In a slicing machine of the character described, the combination with a casing having a hopper, of a drum rotatably mounted in the casing having a closed chute which terminates in an axial circular outlet 40 opening, an inlet slot to the chute being formed through the peripheral face of the drum, a slicing knife secured to the drum and extending partially over said inlet slot means for adjusting the knife to vary the 45 thickness of the slice cut by said knife, slotted portions on opposite sides of said drum, a bolt mounted in said slots and a jam nut on one end of said bolt, an opening being formed in the peripheral face of the 50 drum above said bolt; a sleeve loosely mounted on said bolt, and spaced slitting knives rigidly mounted on the sleeve and which project through the said opening, said slitting knives being in advance of the 55 slicing knife, in the direction of rotation of the drum.

In testimony whereof I affix my signature in presence of two witnesses.

AUGUSTUS L. ENGELBACH.
